UNITED STATES PATENT OFFICE.

BION J. ARNOLD, OF CHICAGO, ILLINOIS.

POWER-TRANSMISSION MECHANISM.

SPECIFICATION forming part of Letters Patent No. 759,222, dated May 10, 1904.

Application filed February 26, 1900. Renewed December 13, 1902. Serial No. 135,165. (No model.)

To all whom it may concern:

Be it known that I, BION J. ARNOLD, a citizen of the United States, residing at Chicago, in the county of Cook and State of Illinois, 5 have invented a certain new and useful Improvement in Power - Transmission Mechanism, (Case No. 3,) of which the following is a full, clear, concise, and exact description, reference being had to the accompanying drawings, forming a part of this specification.

My invention relates to power-transmission mechanism, and more particularly to that class of power-transmission mechanism employed for operating vehicles, although the invention 15 has other application, and has for its object the improvement in construction of such mechanism whereby functions hereinafter more particularly set forth may be performed, and the invention in all of its details will be hereinafter fully described, and set forth in the appended claims.

By means of my invention I am enabled to store the energy that is wasted in braking the wheels of the vehicle and use the same to aid 25 the vehicle-motor in propelling the vehicle— as, for example, in starting vehicles from a state of rest. By means of my invention I am also enabled to use stored energy for aiding the vehicle-motor in climbing grades and 30 to sufficiently retard the travel of the vehicle in descending grades. By means of the apparatus of my invention I make use of that power otherwise wasted in checking and stopping the travel of vehicles.

35 In the preferred embodiment of my invention I employ pneumatic motor mechanism, which may either act as a driving or a driven motor, the construction being preferably such that the pneumatic motor mechanism when 40 being driven will pump air into a confined space, whereby the said mechanism will act as a brake, provision being made to prevent air or other fluid from being stored under too great a pressure, which would cause the vehicle-wheels to skid. For this purpose I preferably 45 employ pop-valve mechanism which is capable of permitting the air to escape when under excessive pressure. The apparatus of my invention thus affords a flexible coupling between the vehicle-motor and the wheels driven

thereby, this flexible connection being such as to operate either as a driving clutch-motor to start the vehicle in motion or as a driven retarder to act as a brake.

My invention in its preferred embodiment 55 relates to electric-traction systems in which single-phase or synchronous or single-phase alternating-current motors may be employed to effect the travel of the vehicle.

As is well understood by those skilled in 60 the art, difficulty has heretofore been experienced in employing the most efficient single-phase alternating-current motors for the propulsion of electric vehicles, a great difficulty 65 residing in means for stopping and starting the motor. The most efficient motors for the purpose are those which will operate with greatest efficiency at synchronism or near synchronism, and those motors technically termed "lag-motors," a type of which is illustrated 70 herein, are the most preferred. I am enabled to permit such motors to operate at most effective speeds and am enabled to secure a speed of the vehicle out of correspondence with the speed of the motor by the employment of 75 variable-speed connection between the vehicle-motor and the vehicle running-gear.

In accordance with my present invention I employ a motor that is preferably constantly operated at a uniform rate of speed irrespective of the speed of the vehicle, and in the preferred embodiment of the invention as employed in electric-traction systems I employ a synchronous motor or a single-phase lag-motor 80 preferably operated at a speed closely approximating synchronism, such motor operating constantly at substantially full speed with the vehicle at rest or traveling at any speed.

85 In operating the vehicle the apparatus of my invention may be first employed to bring the vehicle-motor to speed, after which it may be readjusted to effect engagement between the vehicle-motor and the traction-wheels to propel the vehicle, and the mechanism may also be employed to check and stop the vehicle without modifying the speed of the vehicle-motor.

90 Reference may be had to my copending application.

95 Other features and advantages of my present invention

invention will be more fully hereinafter set forth by reference to the accompanying drawings, in which—

Figure 1 is an elevation, partially in section, of a vehicle-truck equipped with the apparatus of my invention. Fig. 2 is a plan view of the structure shown in Fig. 1, portions of the mechanism being broken away more clearly to reveal the nature of its construction. Fig. 3 is an axial sectional view of a modification of my invention. Fig. 4 is a sectional view on line 3 3 of Fig. 1. Fig. 5 is a longitudinal sectional view of a three-story valve entering into the preferred embodiment of my invention. Figs. 6, 7, and 8 are respectively sectional elevations on lines 6 6, 7 7, and 8 8 of Fig. 5. Figs. 9 and 10 are respectively a sectional elevation and a plan view of a controller-operating handle and indicator. Fig. 11 is a diagrammatic view illustrating the apparatus for controlling the mechanism.

Like parts are indicated by similar characters of reference throughout the different figures.

In Figs. 1, 2, and 3 I have illustrated the truck of an electric vehicle, upon each shaft of which in this instance is mounted a differential clutch-motor α , an electric motor y , and an accelerating and retarding clutch-motor z , all of which are shown fitted to and concentric with the axle b . I will first particularly describe the clutch-motors α and z and will thereafter more fully set forth their operation. The armature of the vehicle or traction motor is fixedly mounted upon the quill-shaft a , as by a key a^2 , which thus becomes the driving-shaft of the vehicle, the said quill-shaft being capable of rotation about the driven shaft or axle b of the vehicle. A gear-support for the clutch-motor α is fixed on the driving-shaft a , the gear c being carried by the said support. The gear-support is preferably in the form of a disk provided with a longitudinally-projecting cylindrical extension, upon the outer end of which extension the gear c is preferably placed and made integral with the gear-support, but from which the gear may be detachable, if desired. Gears d are secured to the axle b , preferably by being attached to the traction-wheels upon the said axle. Frames e^2 for supporting the clutch-motor mechanism are mounted to rotate about the shaft b , the intervening gears or pinions g g' , respectively, engaging the gears d and c of clutch-motor α and the gears d alone of the clutch-motor z , the gears g of clutch-motor α thus intervening between the driving-shaft a and the driven shaft b . Each clutch-motor herein illustrated is in the form of a three-cylinder reciprocating motor, the cylinders of which are formed integrally with the frames e^2 . The pistons h h' , reciprocating within the cylinders, also act as cross-heads with which the connecting-rods

i^2 are pivotally connected at one end, the wrist-pins j having pivotal connection with the connecting-rods i^2 and preferably extending diametrically through the pistons, the said connecting-rods being united with the cranks k k' at the remaining ends. The shafts m m' , rotated by the said cranks, carry gear-wheels g g' . The supports or frames e^2 and most of the parts of the structure immovable with relation thereto may be formed of single castings, as may also the support for the gear c . Bushes l l' are rigidly secured to the shaft b in any suitable way to revolve with it. The supports e^2 are adapted under proper conditions to rotate with respect to the shaft b and the bushes l l' , the bushes being preferably tapered or conical to provide for adjustment compensating for wear. These bushes thus constitute removable wearing-seats for the supports e^2 and valve-seats constituting a part of the clutch-motor mechanism. Air or other fluid is supplied and exhausted alternately through the ports r s and r' s' to drive the pistons h h' , the valving of which fluid is effected as a consequence of the relative rotary motions of the shaft b and supports e^2 . In the particular embodiment of the invention shown the shaft b is provided with an axial bore p , out of which open the ports r r' , s s' , and a passage h^2 . Ports r r' and s s' may be respectively the admission and exhaust ports or respectively the exhaust and admission ports. Under conditions of operation to be hereinafter set forth it may be desirable to maintain clutch-motors z substantially stationary with respect to the fields a' and the vehicle-body. Said fields, as indicated in Fig. 2, are held practically stationary with respect to the car-truck supporting the same. To this end clutching means are employed preferably in the form of electromagnetic clutching mechanism, consisting of coils of wire o , carried in a ring and mounted upon the field portion a' of the electric motor, to which coils current may be passed by means of collector-rings and conductors when the electromagnetic clutch is to be put into service. The support e^2 is preferably enlarged to provide iron projections c' opposite the coils o . The ports r r' and s s' and the corresponding ports n n' in the supports e^2 are so proportioned that air or other fluid under pressure from a suitable source will be admitted under pistons h h' and exhausted from behind pistons h h' at exactly the right moment to cause the cranks m m' to revolve continuously in the predetermined direction. Auxiliary ports q q' are provided in the central or hub portion of the supports e^2 and communicate with reservoirs t t' u u' , formed in the frames e^2 , the said reservoirs or chambers being separated by means of a partition-wall intervening between the same.

Describing generally some features of the mechanism, particularly by reference to Fig.

4, it will be observed that the armature of the motor, being fixed with relation to the quill-shaft a , is adapted to communicate motion to the shaft b through the intermediation of 5 gears c and g of the clutch-motor mechanism x , and the gear d , fixed with relation to the shaft b , engaging the said gears g . By controlling the flow of air or other fluid through the ports r and s the reciprocation of the pistons h of the clutch-motor x may be governed, 10 whereby the rotation of the said gears g about their own axes may be controlled and varied to effect any desired relative speed of the shaft b with respect to the armature of the vehicle traction-motor. The motor mechanism x may also be employed when operating fluid is properly directed therethrough to bring the armature of the vehicle-motor y to speed, whereupon 15 the said armature may be cut into circuit, it being assumed that the vehicle is braked. The supplemental mechanism z is employed to act as a retarding or accelerating engine and does not act as a clutching-engine for uniting the armature of the electric motor with the driving-axle of the vehicle. This 20 engine z when operating has its frame e^2 preferably clutched in engagement with the stationary field of the electric motor flexibly attached to the truck-frame at y' , whereupon 25 by the proper control of actuating fluid admitted to the said engine the same will be operated in one direction to cooperate with the vehicle traction-motor in propelling the vehicle, or the said engine may form a retard- 30 ing means in checking the speed of the vehicle, this engine z thus ordinarily acting as the sole means for braking the vehicle, the pistons thereof performing this function preferably by compressing the air or fluid in a 35 suitable reservoir until the vehicle is stopped, whereupon the valves to the ports of the engine z are closed. The engine z thus acts to accumulate mechanical energy, preferably in the form of compressed air, which may be 40 used, as will be more fully hereinafter set forth. The engines x and z are each provided with reservoirs $t\,u$ and $t'\,u'$, which are preferably fixed with relation to the supporting-frames $e\,e^2$, being preferably formed in integral castings therewith. The arrangement of one of 45 these reservoirs is more clearly illustrated in Fig. 1, each reservoir being comprised in this instance of three reservoir-chambers. Among other conditions of operation to be hereinafter set forth the auxiliary air or fluid engines are adapted to effect the storage of air under pressure in one or the other of the reservoirs $t\,u$ and $t'\,u'$, and the air under pressure in these 50 reservoirs may be used in actuation of the vehicle-operating mechanism. The pistons may when required serve to pump air from one reservoir to its companion reservoir through the communicating valves $r\,s\,r'\,s'$, as hereinafter set forth.

65 In Figs. 5 to 11 I have disclosed the pre-

ferred form of valve mechanism and controlling means that may be employed for effecting the operation of mechanism illustrated in Figs. 2 and 4. The valve-cylinder A contains a three-story ported valve B, ground to fit the 70 interior of the cylinder. The valve-cylinder is provided with an exhaust-port C and a connection D, affording communication between the valve mechanism and the reservoir E. Pipes or ducts F, G, and H afford communication between the accumulator of energy E and the different ports of the engines x and z , the pipes F and G having communication, respectively, with the right and left ends of the bore h^3 in the driving-axle, as shown more 75 clearly in Fig. 4, while the pipe H communicates with the passage h' , leading to said bore h^3 in the driving-axle, as indicated in Fig. 2. I have indicated a switch K for closing current through the clutch-coil o when the valve 80 mechanism is in proper position to have the engines z held from revolving. I preferably employ controllers for governing the operation of the valve B of the form illustrated in Figs. 9 and 10, two such controllers J being 85 diagrammatically indicated in Fig. 11, and one of the controllers being indicated in section and plan in Figs. 9 and 10. A shaft J' is in separable engagement with the handle of the controller, the handle being provided with an 90 extension J^2 , which when the handle registers with the point "0" is in line with a slot in the cap-plate or indicating-dial J^3 of the controller, whereupon the handle may be readily removed. Horizontal shafts J^4 are engaged 95 with vertical shafts J' through miter-gears J^5 , as indicated in the upper portion of Fig. 5. As indicated in Fig. 5 and in Figs. 6, 7, and 8, the pressure-port L, the relief-port M, and the exhaust-port N are formed 100 in and extend lengthwise through the valve B and are so relatively arranged as to present the proper port at the proper time to the corresponding openings or passage-ways C, D, F, G, and H, extending through the 105 valve-cylinder to effect the proper and harmonious control of the engines x and z with relation to the vehicle-motor y . The indicating-dial of the controller J is preferably so marked as to indicate the various operative 110 positions of the rotating valve. A relief-valve O is so arranged that it will allow pressure to pass from port M to the port L if the pressure in the port-passage M exceeds the 115 pressure in the reservoir E, communicating with the port L by the pipe D.

Assuming that the engine z has been operated while retarding the motion of the car (indicated in Fig. 11) sufficiently to store a proper amount of reserve mechanical energy in the 120 form of compressed air or fluid in the reservoir E or that mechanical energy has been otherwise secured in any suitable way, I will proceed to describe the operation of the apparatus of my invention. With the handle of 125

the controller J in the position indicated in Figs. 9 and 10, the pipes F, G, and H are in direct communication with the exhaust-port N, the remaining valve-ports L and M being closed. With this adjustment of the valve mechanism no air is supplied to the engines x and z from the reservoir E, and no air is pumped from the engines to the said reservoir. This is the adjustment of the valve mechanism 5 when the car is stationary and one of the adjustments when the car is to be stopped or reversed. Assuming that the vehicle-motor and the vehicle are stationary, in order to start the vehicle-motor the handle of controller J may be turned backward, say, to point "2," whereupon the valve mechanism will be adjusted to admit fluid under pressure from the supply-tank E to the connecting-pipes G and H, exhaust being permitted from pipe F through 10 the port N and exhaust-pipe N'. The pipe H having communication with the ports of both engines x and z and the pipe G having communication directly with the engines z , the said engines z will remain neutral, while the differential engines x will be operated and will 15 reverse the gearing c and quill-shaft a , carrying the armatures of the vehicle-motors y in a forward direction, sufficient resistance being offered to the gearing d of the engines x by the 20 weight of the car itself to enable these engines x to start the armatures from a state of rest. If the weight of the vehicle is not sufficient for this purpose, the wheels thereof may be 25 braked. When the armatures of the motors are brought to speed or started, they then may be switched into circuit with their source of supply, and thereby maintained at working or synchronous speed, whereupon the handle of the controller may be again placed to the 30 neutral point, as indicated in Fig. 10, in which position the valve mechanism will be so adjusted as to prevent the auxiliary pneumatic engines from effecting coupling engagement 35 between the vehicle-motors and the traction 40 axles and wheels.

In Fig. 4 I have illustrated trolleys connected with the motor-armature and engaging trolley-conductors located along the line of travel.

To replenish the chamber E with compressed air that has been exhausted in bringing the vehicle-motors to speed, the controller-handle may be registered with point "1" forward, the vehicle-wheels still being braked by any suitable means, whereby an adjustment of the 50 valve mechanism will be effected that will bring the pipe F in communication with the relief-port M and the pipes G and H with the exhaust-port N. The auxiliary engines x will thereupon be operated to compress air into 55 the reservoir-chambers t , the air being drawn in through the ports s from the passage h and the exhaust-port N in communication therewith. When the pressure in the reservoir-chambers t exceeds that in the reservoir 60 E, the pop or relief valve O will open and ad-

mit pressure into the tank E. If the brakes upon the traction-wheels are now released, the car will slowly start, owing to the coupling engagement effected between the vehicle-motors and the traction-wheels and axles through 70 the agency of the clutch-engines z , the speed of the car accelerating as the pressure in chambers t of the engines z increases. It will be observed that by moving the handle of the controller contra-clockwise toward point zero 75 the amount of air pumped will be diminished and the pipe F brought more into communication with the exhaust-port N and that when the car is in motion the differential engines x will allow the car to travel at a correspondingly slower speed with relation to the running speed of the vehicle-motor. If the controller-handle is placed at point "2" forward, the pipe F will be brought in direct communication with the pressure-port L, and the engines x will offer a definite resistance or retardation to the revolution of the gears g , whereby the car may be moved by power transmitted from the gearing c , rotated by the armatures of the vehicle-motors to the gearing d through the agency of gearing g . As the controller-handle nears the point "3" forward circuit through the clutch-coil o is completed, preferably by switch K, which closes this circuit when the controller-handle reaches 90 this position. By the adjustment of the controlling-valve mechanism, effected when the controller-handle is moved to this position, air or fluid under pressure is admitted to the pipe G, connected with the accelerating-engines z , which are operated at their full power when the controller-handle reaches the point "3" forward. The differential engines x tend at the same time to force air back into the reservoir-chambers t and the pressure-tank E, whereby 100 elastic connections between the traction-wheels and the vehicle-motors y are effected. The frames e of the accelerating-engines z are maintained stationary with respect to the field portions of the vehicle-motors, whereby upon 105 the reciprocation of the pistons of the engines the gearing g' of the engines z is operated to aid the vehicle-motors in effecting the rotation of the traction-wheels through the turning effort exerted by the gears g' of engines z upon the gears d . The accelerating-engines z thus serve to assist in bringing the car to 110 full speed. After the controller-handle has passed the point "3" forward the switch K is operated to open circuit through the clutch-coil o to disconnect the frames e of engines z from their engagement with the field portions 115 of the vehicle-motors. When the controller-handle is placed at point "4," the pipes F, G, and H are closed and the air in chambers u and u' of the engines x and z is pumped into the chambers t of said engines, thereby causing a 120 vacuum in each of the reservoir-chambers u and u' and pressure in each of the chambers t . With the controlling-valve mechanism in this 125 130

adjustment the internal mechanism of the engines x and z is normally prevented from operating by elastic pressure under the pistons h h' as they tend to move toward the axles of the traction-wheels and a vacuum under each piston as it tends to reciprocate in the opposite direction. The car has now been brought to full speed and is being driven by the vehicle-motors through the agency of clutching differential motors x , which serve to act as flexible connections between the vehicle-motors and the traction-wheels. If the vehicle-motors should need aid in climbing grades, for example, the controller-handle may be turned to point "3" forward, whereupon the engines z will coöperate with the vehicle-motors to propel the car. If, on the other hand, the car should be retarded—as, for example, in descending inclines—the controller-handle is turned in a clockwise direction to point "3" backward. By this adjustment of the controlling-valve mechanism the operation of the engines z will be reversed, the momentum of the car serving to cause the engines z to pump pressure into the tank E, the switch K again serving to clutch the frame e^2 of engines z to field portions of the vehicle-motors when the controller-handle is at point "3" backward. The differential engines x will now permit their gears g to revolve, so that, practically speaking, vehicle-motors y are disconnected from the car, the speed of the car being retarded in proportion to the increasing pressure in the tank E and the pressure in chamber t' in the engines z , which is exerted under the pistons h' of the engines z . As long as the car remains in motion and the controller-handle remains at the point "3" backward pressure or mechanical energy is being stored in the pressure-tank E by the operation of the engines z . When the car has been nearly stopped, the controlling-handle is placed at the point "0," and braking means are then applied to prevent the car from starting from a state of rest until desired. Through the agency of my apparatus I am enabled to cause the car to travel backward, which is frequently desired for short distances, without changing the direction of rotation of the armatures of the vehicle-motors, which may be accomplished by the adjustment of the controlling-valves, effected in placing the controller-handle to the point "3" backward. If it should be desired to cause the car to travel a great distance in the reverse direction, the armatures of the vehicle-motors should cease to rotate, whereupon they may be started or brought to synchronous or working speed in a reverse direction by the reverse operation of the controller-handle, the various steps in the control of the mechanism previously described as being effected by moving the controller-handle forward being now effected by similar movements of the controller-handle backward.

I have illustrated in Fig. 11 duplicated controller-handles and coöperating mechanism, so that the car can be operated from either end. It is also practical to have a plurality of motor-cars in a single train operated from any one platform in unison by any suitable means. 70

In Fig. 3 I have illustrated another embodiment of my improved accelerating and retarding engine in the form of duplicated fluid-motors mounted upon the same shaft. Similar 75 parts in the duplicated portions of the structure illustrated in Fig. 3 are given letters of reference similar to like parts of the engine illustrated in Fig. 4. Passages for the admission and exhaustion of the fluid under pressure are illustrated in the left-hand portion of the structure shown in Fig. 3 as being provided in the axle and in a conical sleeve or bush fixed with relation to the axle, about which the frame e , supporting the reciprocating pistons, 80 is adapted to rotate. Ports or passages for similar purposes are illustrated in the right-hand portion of the structure shown in Fig. 3 located solely within a second bush fixed with relation to the shaft and about which the 85 engine is adapted to rotate. The gear d is secured to the middle portion of the axle, the gears g , engaging the gear d , being common to the duplicated structures. A casting o' serves to unite the frames e^2 of the duplicated 90 engines, as by bolts, and a friction-clutch or brake-band o^2 performs the function of the magnetic clutch o (shown in Fig. 4) in that it may serve to render the frame e^2 stationary 95 with respect to the vehicle. The clutch may 100 be operated in any suitable way. When it is desired to have the engine act as an accelerator, the clutch is applied to maintain the frames e^2 stationary, and air under pressure is supplied to the ports $r r'$ or $s s'$, according to the 105 direction of travel of the vehicle, whereby the engine is operated to exert torque upon the axle. If atmospheric air is supplied through the ports $r r'$ or $s s'$, the engine will pump air, and thereby retard the motion of the car. 110 After the clutch is released the frames e^2 are free to revolve with the axle or driven shaft, thus removing the frictional wear which would otherwise occur in the surface of the cone-bearings and to the working parts of the 115 interior mechanism.

The structure illustrated in Fig. 3 is particularly designed for use upon a vehicle that may have its motor upon one shaft and the auxiliary engine mechanism illustrated in this 120 figure upon another shaft. When the engine mechanism illustrated is to have its frames e^2 rotated freely upon the shaft, the brake-band o^2 may be released from its frictional engagement with the casting o' . When said 125 frames are to remain stationary, the brake o^2 should be applied.

The alternating-current traction-motor (shown more in detail in Fig. 4) has its maximum efficient speed very closely approaching 130

6
synchronism, the particular form of motor there shown being known to engineers as an "alternating-current lag-motor," which while very effective as a motor was hitherto not used for traction purposes for the reasons that have been pointed out. I have not shown a magnetic power connection or other equivalent power connection between the traction-motor and the auxiliary engine in place of the toothed gearing; but I do not wish to be limited to the toothed gearing.

I have illustrated one type of running-gear in the form of flanged traction-wheels united by driving-axles; but I do not wish to be limited to this precise form of running-gear, as other forms thereof may be employed without departing from the spirit of my invention.

I use the term "engine" in the claims broadly, in the sense of any driving-motor.

20 It will be seen that I have provided an engine or motor that is structurally distinct from the prime mover—in this instance the traction-motor on the vehicle—and the load operated by the prime mover—in this instance the vehicle. There is thus, aside from the traction system, provided a power-transmission mechanism.

30 I have shown and particularly described fluid-engines for performing the various functions herein set forth; but it is obvious that other structures and arrangement of structures may be employed, and I do not, therefore, wish to be limited to the precise arrangement and construction of the apparatus of my 35 invention disclosed. Many features herein disclosed I believe to be broadly new with me irrespective of the precise construction and arrangement illustrated, and I therefore desire to claim such features broadly irrespective of 40 the precise instrumentalities employed.

I have disclosed a single-phase alternating-current motor having one member fixed upon the vehicle-body and the other member rotatable with respect to the vehicle-body—that is, one member is rotatable with respect to a point in space and the other member is substantially fixed with respect to said point, assuming the vehicle to be at a standstill. I do not wish to be limited to a construction, however, wherein only one member of the motor is rotatable with respect to a point in space. It will be seen that I have provided a novel vehicle construction wherein there are employed two motors for operating the running-gear, these motors and the running-gear being in tandem operatively—that is, one of these elements occurs after the other in operative relation—one of the motors serving 55 by variation in its speed to regulate the effect of the other motor upon the running-gear. In the system herein disclosed there is employed a single-phase motor having practically a constant speed between its members, which motor is joined to the running-gear by means of 60 a second motor in a manner that has been

fully described. I do not wish to be limited, however, to the location of the motors in the relative order set forth. It will be seen that one motor has a mounting that is substantially fixed with relation to the vehicle body 70 or truck, which motor in the embodiment of the invention set forth is a single-phase motor, the other motor rotatably mounted with respect to the vehicle body or truck and has one of its members adapted for engagement 75 or union with the rotatable element of the aforesaid motor and has the other of its members adapted for engagement or union with the rotating element of the running-gear.

In the drawings I have illustrated a single-motor circuit for supplying a single-phase current to the single-phase motor. I do not wish to be limited, however, to the use of only one single-phase circuit extending along the line of travel, for it is obvious that a generator 80 85 may be employed for supplying the single-phase circuit in operative association with the vehicle, which source of single-phase current may form a part of the complete apparatus that may generate current or currents in addition to that supplied to the single-phase circuit.

Having thus described my invention, I claim as new and desire to secure by Letters Patent—

95

1. In a traction system, the combination with a vehicle, of a vehicle-motor for propelling the same, and a clutching-engine interposed between and coupling the vehicle-motor and the running-gear of the vehicle, said engine serving 100 by variation in its operation to vary the speed of the running-gear with relation to the vehicle-motor, substantially as described.

2. In a traction system, the combination with a vehicle, of a vehicle-motor for propelling the same, a clutching-engine interposed between and coupling the vehicle-motor and the running-gear of the vehicle, and means for supplying a varying amount of power to the said clutching-engine, said engine serving by variation in its operation to vary the speed of the running-gear with relation to the vehicle-motor, substantially as described.

105

3. In a traction system, the combination with a vehicle, of a vehicle-motor for propelling the same, a clutching-engine interposed between the vehicle-motor and the running-gear of the vehicle to couple the vehicle-motor with the said running-gear, said engine serving by variation in its operation to vary the speed of the running-gear in relation to the vehicle-motor, and an additional fluid-engine supplementing the vehicle-motor in controlling the travel of the vehicle, substantially as described.

115

4. In an alternating-current electric-railway system, the combination with a source of alternating current, of a vehicle, an electric motor thereon for effecting the propulsion of the vehicle, a clutching-engine carried by the vehicle interposed between the vehicle-motor 125 130

and the running-gear of the vehicle, serving to couple the said motor and running-gear, and means whereby the said engine may be operated to bring the vehicle-motor to speed, substantially as described.

5 5. In an alternating-current electric-railway system, the combination with a source of alternating current, of a vehicle, an electric motor thereon for effecting the propulsion of the vehicle and receiving current from the said source, a clutching-engine carried by the vehicle interposed between the vehicle-motor and the running-gear of the vehicle, serving to couple the said motor and running-gear, means for storing energy accumulated by the vehicle-motor, and means whereby the said energy is employed to effect the operation of the clutching-engine, substantially as described.

10 6. In an alternating-current electric-railway system, the combination with a source of alternating current, of a vehicle, an electric motor thereon for effecting the propulsion of the vehicle and receiving current from the said source, a clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the clutching-engine, and a second engine supplementing the vehicle-motor in the propulsion of the vehicle, substantially as described.

15 7. In an alternating-current electric-railway system, the combination with a source of alternating current, of a vehicle, an electric motor thereon for effecting the propulsion of the vehicle and receiving current from the said source, a clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the clutching-engine, a second engine supplementing the vehicle-motor in the propulsion of the vehicle, and means for supplying and controlling power operating the latter engine to cause it to aid in the propulsion of the vehicle and to act as a retarding means to check the speed of the vehicle, substantially as described.

20 8. In an alternating-current electric-railway system, the combination with a source of alternating current, of a vehicle, an electric motor thereon for effecting the propulsion of the vehicle and receiving current from the said source, a fluid clutching-engine carried by the vehicle interposed between the vehicle-motor and the running-gear of the vehicle, serving to couple the said motor and running-gear, means for storing energy accumulated by the

is employed to effect the operation of the fluid clutching-engine, and a second engine supplementing the vehicle-motor in the propulsion of the vehicle, substantially as described.

25 9. In an alternating-current electric-railway system, the combination with a source of alternating current, of a vehicle, an electric motor thereon for effecting the propulsion of the vehicle and receiving current from the said source, a fluid clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the fluid clutching-engine, a second engine supplementing the vehicle-motor in the propulsion of the vehicle, and means for supplying and controlling power operating the latter engine to cause it to aid in the propulsion of the vehicle and to act as a retarding means to check the speed of the vehicle, substantially as described.

30 10. In an alternating-current railway system, the combination with a source of alternating current, of a vehicle, an electric motor thereon for effecting its propulsion and receiving current from the said source, and a fluid clutching-engine interposed between the vehicle-motor and the running-gear of the vehicle to couple the said motor and running-gear, said engine serving by variation in its operation to vary the speed of the running-gear with relation to the vehicle-motor, substantially as described.

35 11. In an alternating-current railway system, the combination with a source of alternating current, of a vehicle, an electric motor thereon for effecting its propulsion and receiving current from the said source, a fluid clutching-engine interposed between the vehicle-motor and the running-gear of the vehicle to couple the said motor and running-gear, means for storing power accumulated by the electric motor, and means for effecting the application of said power to the said clutching-engine, substantially as described.

40 12. In an alternating-current railway system, the combination with a source of alternating current, of a vehicle, an electric motor thereon for effecting its propulsion and receiving current from the said source, a fluid clutching-engine interposed between the vehicle-motor and the running-gear of the vehicle to couple the said motor and running-gear, means for storing power accumulated by the electric motor, means for effecting the application of said power to the said clutching-engine, a second fluid-engine for accelerating and retarding the motion of the vehicle, and means for controlling the application of the said stored energy to the latter engine, substantially as described.

45 13. In a traction system, the combination

with a vehicle, of a vehicle-motor carried thereby, a variable-speed fluid clutching-engine for coupling the vehicle-motor with the running-gear of the vehicle, and a second fluid-engine for accelerating and checking the speed of the vehicle, substantially as described.

14. In a traction system, the combination with a vehicle, of a vehicle-motor carried thereby, a fluid clutching-engine for coupling the vehicle-motor with the running-gear of the vehicle, a second fluid-engine for accelerating and checking the speed of the vehicle, means for storing energy accumulated by said vehicle-motor, and means for controlling the application of said energy to effect the operation of said engines, substantially as described.

15. In a traction system, the combination with a vehicle, of a vehicle-motor carried thereby, a fluid clutching-engine for coupling the vehicle-motor with the running-gear of the vehicle, a second fluid-engine for accelerating and checking the speed of the vehicle, means for rendering the frame of the latter engine substantially stationary, whereby the said engine may operate to pump the fluid, means for storing the fluid which is pumped, and means for controlling the application of said fluid to effect the operation of said engines, substantially as described.

16. In a traction system, the combination with a vehicle, of a vehicle-motor for effecting the propulsion thereof, an accelerating and retarding engine coöperating with the vehicle-motor to control the travel of the vehicle, means for admitting power to said engine to enable it to coöperate with the vehicle-motor to accelerate the speed of the vehicle, means for reversing the action of the engine to check the travel of the vehicle, means whereby said engine may in conjunction with the motor move the vehicle faster than the vehicle could be moved by the motor alone and means for storing energy accumulated by the said engine when operating to check the travel of the vehicle, substantially as described.

17. In a traction system, the combination with a vehicle, of a motor for propelling the same, a retarding fluid-engine for checking the travel of the vehicle, means for storing the fluid pumped by the said engine while acting to check the travel of the vehicle, means for operating said engine to effect propulsion of the vehicle in coöperation with the motor, means whereby said engine may, in conjunction with the motor, move the vehicle faster than the vehicle could be moved by the motor alone, substantially as described.

18. In a traction system, the combination with a vehicle, of a motor for propelling the same, a retarding fluid-engine for checking the travel of the vehicle, means for storing the fluid pumped by the said engine while acting to check the travel of the vehicle, means for applying said stored energy to effect the operation of the said engine to accelerate the speed

of the vehicle, means whereby said engine may, in conjunction with the motor, move the vehicle faster than the vehicle could be moved by the motor alone, substantially as described.

19. In a traction system, the combination with a vehicle, of a motor carried thereby for propelling the same, and a retarding-engine interposed between the motor and the running-gear to check the speed of the vehicle, substantially as described.

20. In a traction system, the combination with a vehicle, of a motor carried thereby for propelling the same, a retarding-engine interposed between the motor and the running-gear to check the speed of the vehicle, and means for storing the energy accumulated by the retarding-engine, substantially as described.

21. In a traction system, the combination with a vehicle, of a motor carried thereby for propelling the same, a retarding and accelerating engine interposed between the motor and the running-gear to check the speed of the vehicle, means for storing the energy accumulated by the retarding and accelerating engine, and means for controlling the application of the stored energy to the said engine to effect its operation to accelerate the speed of the vehicle, substantially as described.

22. In a traction system, the combination with a vehicle, of a motor for propelling the same, an engine engaging the running-gear of the vehicle, means for supplying the said engine with power to start the motor, and means whereby the motor may operate the engine without propelling the vehicle to replenish power used in starting the motor, substantially as described.

23. In a traction system, the combination with a vehicle, of a motor to drive the vehicle, an engine adapted for operative connection with the running-gear of the vehicle, means whereby the said engine may operate to check the speed of the vehicle, means for storing the energy accumulated by the engine when thus operated, means for supplying the engine with power to aid the said motor in the propulsion of the vehicle, means whereby the said engine may, in conjunction with the motor, move the vehicle faster than the vehicle could be moved by the motor alone, substantially as described.

24. In a power-transmitting mechanism, the combination with a motor, of a driven member, an engine engaging the driven member, means for supplying the said engine with power to start the motor, and means whereby the motor may operate the engine without operating the driven member to replenish power used in starting the motor, substantially as described.

25. In a power-transmitting mechanism, the combination with a motor serving to drive a load, of an engine adapted for operative connection with the said load, means whereby the said engine may operate to check the speed of the load, means for storing the energy ac-

cumulated by the engine when thus operated, means for supplying the engine with power to aid the said motor in the operation of the load, means whereby said engine may, in conjunction with the motor, move the vehicle faster than the vehicle could be moved by the motor alone, substantially as described.

26. In a power-transmitting mechanism, the combination with a motor for driving a load, of an engine adapted to be driven by the load to retard the operation of the load, means for holding the frame of the engine substantially immovable, and means for supplying power to said engine to aid in the operation of the load, the means for holding the frame of the engine substantially immovable being adjustable to also permit the bodily movement of the said frame, whereby operative connection between the engine and the load is severed, substantially as described.

27. In a power-transmitting mechanism, the combination with a revoluble shaft, of a motor for rotating the same, an engine having its frame revoluble with relation to the said shaft, the said engine being adapted for operative connection with the shaft, and means whereby the rotation of the engine-frame may be checked to effect coöperative engagement between the shaft and engine, substantially as described.

28. In a traction system, the combination with a vehicle, of a vehicle-motor for effecting the propulsion thereof, an accelerating and retarding engine coöperating with the vehicle-motor to control the travel of the vehicle, means for admitting power to said engine to enable it to coöperate with the vehicle-motor to accelerate the speed of the vehicle, means for reversing the action of the engine to check the travel of the vehicle, means for storing energy accumulated by the said engine when operating to check the travel of the vehicle, means whereby the accumulated energy may serve to actuate the said engine to aid in the propulsion of the vehicle, means whereby said engine may, in conjunction with the motor, move the vehicle faster than the vehicle could be moved by the motor alone, substantially as described.

29. In a traction system, the combination with a vehicle, of a vehicle-motor for effecting the propulsion thereof, an accelerating and retarding engine coöperating with the vehicle-motor to control the travel of the vehicle, means for admitting power to said engine to enable it to coöperate with the vehicle-motor to accelerate the speed of the vehicle, means for reversing the action of the engine to check the travel of the vehicle, means for storing mechanical energy accumulated by the said engine when operating to check the travel of the vehicle, means whereby said engine may, in conjunction with the motor, move the vehicle faster than the vehicle could be moved by the motor alone, substantially as described.

30. In a traction system, the combination with a vehicle, of a vehicle-motor for effecting the propulsion thereof, an accelerating and retarding engine coöperating with the vehicle-motor to control the travel of the vehicle, means for admitting power to said engine to enable it to coöperate with the vehicle-motor to accelerate the speed of the vehicle, means for reversing the action of the engine to check the travel of the vehicle, means for storing mechanical energy accumulated by the said engine when operating to check the travel of the vehicle, means whereby the accumulated energy may serve to actuate the said engine to aid in the propulsion of the vehicle, means whereby said engine may, in conjunction with the motor, move the vehicle faster than the vehicle could be moved by the motor alone, substantially as described.

31. In a traction system, the combination with a vehicle, of a motor for propelling the same, means for storing energy accumulated in the operation of the vehicle, and an engine adapted for operation by the said energy and adapted for engagement with the vehicle-motor to start the same, substantially as described.

32. In a traction system, the combination with a vehicle, of a vehicle-motor for effecting its propulsion, means for storing energy accumulated by the vehicle-motor, and an engine operated by the energy and adapted for engagement with the vehicle-motor to start the same, substantially as described.

33. In a traction system, the combination with a vehicle, of an electric vehicle-motor for propelling the same, a source of single-phase alternating current for operating the motor and having conducting means located along the line of travel, means for storing energy accumulated by the vehicle in its operation, and an engine adapted for operation by said energy and serving to engage and start the vehicle-motor, substantially as described.

34. In a traction system, the combination with a vehicle, of an electric vehicle-motor for propelling the same, a source of single-phase alternating current for operating the motor and having conducting means located along the line of travel, means for storing energy accumulated by the vehicle-motor, and an engine adapted for operation by said energy and serving to engage and start the vehicle-motor, substantially as described.

35. The combination with a vehicle, of a traction-motor thereon, an auxiliary engine interposed between the traction-motor and the running-gear of the vehicle, and adapted to constitute a connection between the vehicle-motor and the running-gear, and means whereby the motor and engine may together effect speed out of correspondence with the rate of speed of the motor, substantially as described.

36. The combination with a prime mover or motor and its load, of an auxiliary engine in-

terposed between the prime mover and its load and constituting a connection between the same, and means whereby the motor and engine may together effect speed out of correspondence with the rate of speed of the motor, substantially as described.

37. The combination with a prime mover, of a driven member or load operated thereby, rotatable means connecting both members, and means for driving the aforesaid means independently of the prime mover, substantially as described.

38. The combination with the prime mover, a load or driven member operated thereby, a power-transmitting means driven independently of the prime mover interposed and transmitting power between the said prime mover and the driven member, and means whereby the prime mover and power-transmitting means may together effect speed out of correspondence with the rate of speed of the prime mover, substantially as described.

39. In combination, a prime mover, a driven member and an independently-driven motor connecting said prime mover and driven member, and means whereby the prime mover and motor may together effect speed out of correspondence with the rate of speed of the prime mover, substantially as described.

40. In combination a prime mover, a driven member, and a motor connecting the same that is structurally distinct from the driven member, and means whereby the prime mover and motor may together effect speed out of correspondence with the rate of speed of the prime mover, substantially as described.

41. In combination, a prime mover, a driven member and a motor connecting the same which is structurally distinct from the prime mover, and means whereby the prime mover and motor may together effect speed out of correspondence with the rate of speed of the prime mover, substantially as described.

42. In combination, a prime mover, a driven member, and a motor connecting the same that is structurally distinct from the prime mover and driven member, and means whereby the prime mover and motor may together effect speed out of correspondence with the rate of speed of the prime mover, substantially as described.

43. In a traction system, the combination with a vehicle, of a motor for propelling the same, an engine engaging the running-gear of the vehicle, means for supplying the said engine with power to actuate the motor, and means whereby the motor may operate the engine without propelling the vehicle to replenish power used in actuating the motor, substantially as described.

44. In a traction system, the combination with a vehicle, of a vehicle-motor for effecting the propulsion thereof, an accelerating and retarding engine cooperating with the vehicle-motor to control the travel of the ve-

hicle, means for admitting power to said engine to enable it to coöperate with the vehicle-motor to accelerate the speed of the vehicle, means whereby the said motor and engine may together produce a speed of the vehicle above that which could be produced by the motor alone, means for reversing the action of the engine to check the travel of the vehicle, means for storing energy accumulated by the said engine when operating to check the travel of the vehicle, and means whereby the stored power may be employed in operating the engine, substantially as described.

45. In a traction system, the combination with a vehicle, of a motor carried thereby for propelling the same, a retarding-engine interposed between the motor and the running-gear to check the speed of the vehicle, and means for storing the energy accumulated by the retarding-engine, and means for applying said energy to effect operation of the engine, substantially as described.

46. In a traction system, the combination with a vehicle, of a constant-speed electric motor carried thereby for propelling the same, an engine constituting a power connection between the motor and running-gear, and means whereby the engine and motor jointly may effect travel of the vehicle out of correspondence with the rate of speed of the constant-speed motor, substantially as described.

47. In a traction system, the combination with a vehicle, of a synchronous single-phase alternating-current motor carried thereby for propelling the same, an engine constituting a power connection between the motor and running-gear, and means whereby the engine and motor jointly may effect travel of the vehicle out of correspondence with the rate of speed of the synchronous motor, substantially as described.

48. In a traction system, the combination with a vehicle, of an alternating-current motor carried thereby for propelling the same, and a fluid-engine interposed between the motor and the running-gear, substantially as described.

49. In a traction system, the combination with a vehicle, of a single-phase alternating-current motor carried thereby for propelling the same, and a fluid-engine interposed between the motor and the running-gear, substantially as described.

50. In a power-transmitting mechanism, the combination with a revoluble shaft, of a motor for rotating the same, an engine having its frame revoluble with relation to the shaft, the said engine being adapted for operative connection with the shaft and means whereby the rate of rotation of the engine-frame may be varied to effect coöoperative engagement between the shaft and engine, substantially as described.

51. In a traction system, the combination with a revoluble shaft constituting part of the

- running-gear of a vehicle, of a vehicle traction-motor for rotating the shaft, an engine having its frame revoluble with relation to the shaft, the said engine being adapted for operative connection with the shaft, and means whereby the rotation of the engine-frame may be checked to effect coöperative engagement between the running-gear shaft and engine, substantially as described.
52. In a traction system, the combination with a revoluble shaft, constituting part of the running-gear of a vehicle, of a vehicle traction-motor for rotating the shaft, an engine having its frame revoluble with relation to the shaft, the said engine being adapted for operative connection with the shaft, and means whereby the rate of rotation of the engine-frame may be varied to effect coöperative engagement between the running-gear shaft and engine, substantially as described.

53. The combination with a vehicle, of a traction-motor thereon, an auxiliary engine or motor and means whereby the engine and traction-motor may together effect a speed of the vehicle out of correspondence with the rate of speed of the traction-motor, substantially as described.

54. In a traction system, the combination with a vehicle of a constant-speed traction-motor thereon for operating the same, an auxiliary engine on the vehicle constituting a power connection between the motor and vehicle running-gear, and means whereby said motor and engine may jointly effect travel of the vehicle out of correspondence with the speed of the traction-motor, substantially as described.

55. In a traction system, the combination with a vehicle, of an electric motor carried thereby for propelling the same, an engine on the vehicle constituting a power connection between the motor and the vehicle running-gear, and means whereby the motor and engine may jointly operate the vehicle out of correspondence with the speed of said motor, substantially as described.

56. In a railway system, the combination with a vehicle, of mechanically-engaged motors, and means whereby the speed of the vehicle may be effected by said motors out of correspondence with the speed of one of the motors, substantially as described.

57. In a railway system, the combination with a vehicle, of a substantially constant speed motor, an additional motor in mechanical engagement with the aforesaid motor, and means whereby the said motor may effect travel of the vehicle out of correspondence with the speed of the first motor, substantially as described.

58. In an electric-railway system, the combination with a supply-circuit extending along the line of travel and including a source of single-phase alternating current, of a vehicle, a single-phase alternating-current motor, means

whereby the said motor is supplied with single-phase alternating current from said supply-circuit to operate it, a second motor in mechanical engagement with the aforesaid motor, and means whereby these motors may together effect travel of the vehicle out of correspondence with the speed of the single-phase motor, substantially as described.

59. In an electric-railway system, the combination with a supply-circuit extending along the line of travel and including a source of single-phase alternating current, of a vehicle, a single-phase alternating-current motor, means whereby the said motor is supplied with single-phase alternating current from the said supply-circuit to operate it, a second motor in mechanical engagement with the aforesaid motor, means whereby these motors may together effect travel of the vehicle out of correspondence with the speed of the single-phase motor, and means for starting the single-phase motor, substantially as described.

60. In an electric-railway system, the combination with a supply-circuit extending along the line of travel and including a source of single-phase alternating current, of a vehicle, a single-phase alternating-current motor in driving engagement with the running-gear of the vehicle, means whereby the said motor is supplied with single-phase alternating current from the said supply-circuit, and means whereby the said motor may operate the vehicle at varying rates of speed out of correspondence with the motor speed, substantially as described.

61. In an electric-railway system, the combination with a supply-circuit extending along the line of travel and including a source of single-phase alternating current, of a vehicle, a single-phase alternating-current motor, means whereby the said motor is supplied with single-phase alternating current from said supply-circuit, and a variable-speed connection between the motor and the running-gear of the vehicle, whereby the vehicle may be operated at speeds out of correspondence with the motor speed, substantially as described.

62. In an electric-railway system, the combination with a supply-circuit extending along the line of travel and including a source of single-phase alternating current, of a vehicle, a single-phase alternating-current motor in driving engagement with the running-gear of the vehicle, means whereby the said motor is supplied with single-phase alternating current from the said supply-circuit, means whereby the said motor may operate the vehicle at varying rates of speed out of correspondence with the motor speed, and means whereby the vehicle-motor may be started, substantially as described.

63. In an electric-railway system, the combination with a supply-circuit extending along the line of travel and including a source of single-phase alternating current, of a vehicle, a

- single-phase alternating-current motor, means whereby the said motor is supplied with single-phase alternating current from the said supply-circuit, and a variable gear speed connection uniting the said motor with the running-gear of the vehicle, whereby the vehicle may be operated at speeds out of correspondence with the motor speed, substantially as described.
64. In an alternating-current electric-railway system, the combination with a source of single-phase alternating current, of a vehicle, a single-phase electric motor thereon for effecting the propulsion of the vehicle, a clutching-engine carried by the vehicle interposed between the vehicle-motor and the running-gear of the vehicle, serving to couple the said motor and running-gear, and means whereby the said engine may be operated to bring the vehicle-motor to speed, substantially as described.
65. In an alternating-current electric-railway system, the combination with a source of single-phase alternating current, of a vehicle, a single-phase electric motor thereon for effecting the propulsion of the vehicle and receiving current from the said source, a clutching-engine carried by the vehicle interposed between the vehicle-motor and the running-gear of the vehicle, serving to couple the said motor and running-gear, means for storing energy accumulated by the vehicle-motor, and means whereby the said energy is employed to effect the operation of the clutching-engine, substantially as described.
66. In an alternating-current electric-railway system, the combination with a source of single-phase alternating current, of a vehicle, a single-phase electric motor thereon for effecting the propulsion of the vehicle and receiving current from the said source, a clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the clutching-engine, and a second engine supplementing the vehicle-motor in the propulsion of the vehicle, substantially as described.
67. In an alternating-current electric-railway system, the combination with a source of single-phase alternating current, of a vehicle, a single-phase electric motor thereon for effecting the propulsion of the vehicle and receiving current from the said source, a clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the clutching-engine, a second engine supplementing the vehicle-motor in the propulsion of the vehicle, and means

for supplying and controlling power operating the latter engine to cause it to aid in the propulsion of the vehicle and to act as a retarding means to check the speed of the vehicle, substantially as described.

68. In an alternating-current electric-railway system, the combination with a source of single-phase alternating current, of a vehicle, a single-phase electric motor thereon for effecting the propulsion of the vehicle and receiving current from the said source, a fluid clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the fluid clutching-engine, and a second engine supplementing the vehicle-motor in the propulsion of the vehicle, substantially as described.

69. In an alternating-current electric-railway system, the combination with a source of single-phase alternating current, of a vehicle, a single-phase electric motor thereon for effecting the propulsion of the vehicle and receiving current from the said source, a fluid clutching-engine carried by the vehicle interposed between the vehicle-motor and the running-gear of the vehicle, serving to couple the said motor and running-gear, means for storing energy accumulated by the vehicle-motor, means whereby the said energy is employed to effect the operation of the fluid clutching-engine, a second engine supplementing the vehicle-motor in the propulsion of the vehicle, substantially as described.

70. In an alternating-current railway system, the combination with a source of single-phase alternating current, of a vehicle, a single-phase electric motor thereon for effecting its propulsion and receiving current from the said source, a fluid clutching-engine interposed between the vehicle-motor and the running-gear of the vehicle to couple the said motor and running-gear, means for storing power accumulated by the electric motor, and means for effecting the application of said power to the said clutching-engine, substantially as described.

71. In an alternating-current railway system, the combination with a source of single-phase alternating current, of a vehicle, a single-phase electric motor thereon for effecting its propulsion and receiving current from the said source, a fluid clutching-engine interposed between the vehicle-motor and the running-gear of the vehicle to couple the said motor and running-gear, means for storing power accumulated by the electric motor, means for effecting the application of said power to the

said clutching-engine, a second fluid-engine for accelerating and retarding the motion of the vehicle, and means for controlling the application of the said stored energy to the latter engine, substantially as described.

72. In an alternating-current railway system, the combination with a source of single-phase alternating current, of a vehicle, a single-phase electric motor thereon for effecting its propulsion and receiving current from the said source, and a fluid clutching-engine interposed between the vehicle-motor and the running-gear of the vehicle to couple the said motor and running-gear, said engine serving by variation in its operation to vary the speed of the running-gear with relation to the vehicle-motor, substantially as described.

73. The combination with a vehicle, of two motors, the running-gear of the vehicle and the two motors being connected in tandem or series operatively, substantially as described.

74. The combination with a vehicle, of a single-phase motor thereon employed in propelling the same and a second motor in driving connection with the single-phase motor, and thereby serving to operate the vehicle out of correspondence with the speed between the armature and field of the single-phase motor, the said motors and the running-gear of the vehicle being in tandem connection or arrangement, substantially as described.

75. The combination with a vehicle, of a single-phase motor thereon employed in propelling the same and a second motor in driving connection with the single-phase motor, and thereby serving to operate the vehicle out of correspondence with the speed between the armature and field of the single-phase motor, a circuit along the line of travel, including a source of single-phase current and means for supplying the said single-phase motor with single-phase current from said circuit, substantially as described.

76. The combination with a vehicle, of two motors, the running-gear of the vehicle and the two motors being connected in tandem or series operatively, a circuit on the line of travel including a source of single-phase current, and means for supplying the said single-phase motor with single-phase current from said circuit, substantially as described.

77. The combination with a vehicle, of a single-phase motor thereon employed in propelling the same and a second motor in driving connection with the single-phase motor, and thereby serving to operate the vehicle out of correspondence with the speed between the armature and field of the single-phase motor, a circuit along the line of travel, including a source of single-phase current and a trolley and connections carried by the vehicle for supplying the said single-phase motor with single-phase current from said circuit, substantially as described.

78. The combination with a vehicle, of a mo-

tor having a mounting substantially fixed with respect to the body of the vehicle and a second motor having one element in connection with the rotating element of the aforesaid motor and the other element in connection with the running-gear, substantially as described.

79. The combination with a vehicle, of a motor having a mounting substantially fixed with respect to the body of the vehicle and a second motor having one element in connection with the rotating element of the aforesaid motor and the other element in connection with the running-gear, one of the said motors having substantially constant speed between its members and means whereby the speed between members of the other motor may be varied, substantially as described.

80. The combination with a vehicle, of a motor having a mounting substantially fixed with respect to the body of the vehicle and a second motor having one element in connection with the rotating element of the aforesaid motor and the other element in connection with the running-gear, one of the said motors being substantially a constant-speed single-phase motor and means whereby the speed between members of the other motor may be varied, substantially as described.

81. The combination with a vehicle, of a motor having a mounting substantially fixed with respect to the body of the vehicle and a second motor having one element in connection with the rotating element of the aforesaid motor and the other element in connection with the running-gear, one of the said motors being substantially a constant-speed single-phase motor, means whereby the speed between members of the other motor may be varied, a source of single-phase current included in a supply-circuit extending along the line of travel, and means carried by the vehicle for transferring the current from this supply-circuit to the single-phase motor, substantially as described.

82. The combination with a vehicle, of a motor having a mounting substantially fixed with respect to the body of the vehicle and a second motor having one element in connection with the rotating element of the aforesaid motor and the other element in connection with the running-gear, one of the said motors being substantially a constant-speed single-phase motor, and a trolley with its connections for supplying the single-phase motor with current from the said supply-circuit, substantially as described.

83. The combination with a vehicle, of a motor having a mounting substantially fixed with respect to the body of the vehicle and a second motor having one element in connection with the rotating element of the aforesaid motor and the other element in connection with the running-gear, one of the said motors being substantially a constant-speed single-phase motor, means whereby the speed between

members of the other motor may be varied, a source of single-phase current included in a supply-circuit extending along the line of travel, means carried by the vehicle for transmitting the current from this supply-circuit to the single-phase motor, means for storing energy accumulated by the vehicle's operating mechanism, and controlling means whereby this energy may be used in regulating the speed of that motor coupled in association with the single-phase motor, substantially as described.

84. In a traction system, the combination with a vehicle, of a constant-speed motor carried thereby for propelling the same, an engine carried by the vehicle, said motor and engine being in vehicle-driving engagement with the vehicle's running-gear, and means whereby said motor and engine may together operate the vehicle at speed out of correspondence with the speed of the constant-speed motor, substantially as described.

85. In a traction system, the combination with a vehicle, of a constant-speed electric motor carried thereby for propelling the same, an engine carried by the vehicle, said motor and engine being in vehicle-driving engagement with the vehicle's running-gear, and means whereby said motor and engine may together operate the vehicle at speed out of correspondence with the speed of the motor, substantially as described.

86. In a traction system, the combination with a vehicle, of a synchronous single-phase alternating-current motor carried thereby for propelling the same, an engine on the vehicle, said motor and engine being in vehicle-driving engagement with the vehicle's running-gear, and means whereby said motor and engine may together operate the vehicle at speed out of correspondence with the speed of the motor, substantially as described.

87. In a traction system, the combination with a vehicle, of an electric traction-motor thereon for operating the same, an auxiliary engine on the vehicle, said motor and engine being in vehicle-driving engagement with the vehicle's running-gear, and means whereby said motor and engine may jointly effect travel of the vehicle out of correspondence with the rate of speed of the traction-motor, substantially as described.

88. In an electric-railway system, the combination with a vehicle, of a supply-circuit extending along the line of travel of the vehicle and including a source of single-phase alternating current, a single-phase traction-motor on the vehicle having separable vehicle-driving connection with the vehicle's running-gear, means for supplying the said motor with single-phase alternating current from the said supply-circuit, and means capable of actuating the motor without operating the vehicle and bringing the said motor to synchronism, substantially as described.

89. In an electric-railway system, the combination with a vehicle, of a supply-circuit extending along the line of travel of the vehicle and including a source of single-phase alternating current, a single-phase traction-motor on the vehicle having separable vehicle-driving connection with the vehicle's running-gear, means for supplying the said motor with single-phase alternating current from the said supply-circuit, and motive means capable of actuating the motor without operating the vehicle and bringing the said motor to synchronism, substantially as described. 70

90. In an electric-railway system, the combination with a vehicle, of a supply-circuit extending along the line of travel of the vehicle and including a source of single-phase alternating current, a single-phase traction-motor on the vehicle having variable-gear or vehicle-driving speed connection with the vehicle's running-gear, means for supplying the said motor with single-phase alternating current from said supply-circuit, and means for bringing the motor to synchronism, substantially as described. 80

91. In an electric-railway system, the combination with a vehicle, of a supply-circuit extending along the line of travel of the vehicle and including a source of single-phase alternating current, a single-phase traction-motor 95 having a variable-gear or vehicle-driving speed connection with the vehicle's running-gear, means for supplying the said motor with single-phase alternating current from said supply-circuit, and motive means for bringing the motor to synchronism, substantially as described. 100

92. In an electric-railway system, the combination with a vehicle, of a supply-circuit extending along the line of travel of the vehicle, and including a source of single-phase alternating current, a single-phase traction-motor on the vehicle having variable-gear or vehicle-driving speed connection with the vehicle's running-gear, means for supplying the said motor with single-phase alternating current from said supply-circuit, and means for actuating the motor without operating the vehicle and bringing the said motor to synchronism, substantially as described. 105

93. In an electric-railway system, the combination with a vehicle of a supply-circuit extending along the line of travel of the vehicle, and including a source of single-phase alternating current, a single-phase traction-motor 120 on the vehicle having variable-gear or vehicle-driving speed connection with the vehicle's running-gear, means for supplying the said motor with single-phase alternating current from said supply-circuit, and motive means 125 for actuating the motor without operating the vehicle and bringing the said motor to synchronism, substantially as described.

94. In an electric-railway system, the combination with a vehicle, of a supply-circuit ex- 130

tending along the line of travel of the vehicle and including a source of single-phase alternating current, a single-phase motor on the vehicle in driving engagement with the vehicle's running-gear, means for supplying the said motor with a single-phase alternating current from said supply-circuit, and means for starting the motor and for effecting a variable speed of travel of the vehicle, substantially as described.

95. In a railway system, the combination with a vehicle, of a substantially constant speed motor in driving engagement with the vehicle's running-gear, an additional motor, and means whereby the said motor may effect travel of the vehicle out of correspondence with the speed of the first motor, substantially as described.

96. In an electric-railway system, the combination with a supply-circuit extending along the line of travel and including a source of single-phase alternating current, of a vehicle, a single-phase alternating-current motor in driving engagement with the vehicle's running-gear, means whereby the said motor is supplied with single-phase alternating current from said supply-circuit to operate it, a second motor, and means whereby these motors may together effect travel of the vehicle out of correspondence with the speed of the single-phase motor, substantially as described.

97. In an electric-railway system, the combination with a supply-circuit extending along

the line of travel and including a source of single-phase alternating current, of a vehicle, a single-phase alternating-current motor in driving engagement with the vehicle's running-gear, means whereby the said motor is supplied with single-phase alternating current from said supply-circuit to operate it, a second motor, means whereby these motors may together effect travel of the vehicle out of correspondence with the speed of the single-phase motor, and means for starting the single-phase motor, substantially as described.

98. In an electric-railway system, the combination with a supply-circuit extending along the line of travel and including a source of single-phase alternating current, of a vehicle, a single-phase alternating-current motor in vehicle-driving engagement with the vehicle's running-gear, means whereby the said motor is supplied with single-phase alternating current from the said supply-circuit, a variable-speed connection uniting the motor and the running-gear of the vehicle, whereby the vehicle may be operated at speeds out of correspondence with the motor speed, and means whereby the vehicle-motor may be started, substantially as described.

In witness whereof I hereunto subscribe my name this 23d day of February, A. D. 1900.

BION J. ARNOLD.
